UNITED STATES PATENT OFFICE.

RAY H. MANSON, OF ELYRIA, OHIO, ASSIGNOR TO THE GARFORD MANUFACTURING COMPANY, OF ELYRIA, OHIO, A CORPORATION OF OHIO.

DESIGN FOR A PUSH-BUTTON CIRCUIT-CONTROLLER.

49,126.

Specification for Design.

Patented May 30, 1916.

Application filed July 26, 1915. Serial No. 42,075. Term of patent 7 years.

To all whom it may concern:

Be it known that I, RAY H. MANSON, a citizen of the United States, residing at Elyria, in the county of Lorain and State of Ohio, have invented a new, original, and ornamental Design for Push-Button Circuit-Controllers, of which the following is a specification, reference being made to the accompanying drawing, forming a part thereof.

Figure 1 is a side elevation of a push button circuit controller illustrating my new design. Fig. 2 is a plan view of the embodiment shown in Fig. 1.

I claim:

The ornamental design for a push button circuit controller, as shown.

RAY H. MANSON.
